UNITED STATES PATENT OFFICE.

EDWIN B. SCHMUCKER, OF NORFOLK, VIRGINIA.

INFANT'S HIGH CHAIR.

1,060,503.

Specification of Letters Patent. Patented Apr. 29, 1913.

Application filed November 22, 1910. Serial No. 593,732.

To all whom it may concern:

Be it known that I, EDWIN B. SCHMUCKER, a citizen of the United States, residing at Norfolk, in the county of Norfolk and State 5 of Virginia, have invented new and useful Improvements in Infants' High Chairs, of which the following is a specification.

This invention relates to infants' high chairs and more particularly to the tables 10 used in connection therewith.

The object of the invention is the provision of a table which may be readily applied to an infant's high-chair and be operated within the space occupied by the 15 chair and avoids the use of the extra arms necessary where the table is hinged to the back of the chair and swings over the same.

A further object of the invention is the provision of a table adapted to be positioned 20 across the arms of the ordinary high-chair and which can be operated with the chair close to the wall on either side or behind the chair thus greatly economizing room space and at the same time providing a table 25 which obviates the danger of striking the child upon the head when thrown to operative position.

A further object of the invention is the provision of a novel hinge for mounting the 30 table so as to permit vertical and lateral movement thereof and further means to prevent lateral movement of the table when in operative position.

Further objects of the invention will appear as the following specific description is 35 read in connection with the accompanying drawing which forms a part of this application, and in which:

Figure 1 is a front elevation showing the 40 table in operative position in full lines and in inoperative position in dotted lines. Fig. 2 is a detail top plan view of the chair with the table in inoperative position. Fig. 3 is a detail side elevation of the chair with the 45 table in operative position. Fig. 4 is a detail vertical sectional view.

Referring more particularly to the drawings 50 1 represents the ordinary high-chair having the side arms 2 and 3 upon one of which is secured the hinge 4 comprising a flat attaching leaf 5 and a leaf 6 which has its ends upturned as at 7 so as to form guiding flanges which are adapted to receive the side edges of the table 8. The table having 55 reduced edges which are slidably mounted between the upturned flanges of leaf 6 as

shown and is limited in one direction by a pin 9 which is secured to the underside of the table and is adapted to engage the leaf 6. The table is prevented from becoming disengaged from the leaf 6 when in inoperative position by means of a pin 10 which projects below the table from the opposite end to that having the pin 9 and is adapted to engage upon the attaching leaf 5 as shown in dotted lines in Fig. 1. This pin is also adapted to enter an aperture 11 formed in the upper side of the arm 3 as shown in section in Fig. 4 so as to prevent lateral movement of the table or transverse movement thereof across the chair. A suitable spring catch 12 is provided which may be of any suitable design to lock the free end of the table when the same is in operative position.

In the operation of the device, when it is desired to place the table in operative position, it is moved vertically from the position shown in dotted lines in Fig. 1, sliding through the leaf 6 until the pin 9 contacts therewith and then the free end of the table is lowered into contact with the arm 3. The pin 10 enters the hole 11 and prevents lateral displacement of the table and also any transverse movement thereof across the chair and the spring catch 12 prevents the infant from raising the table and spilling the contents thereof.

Having thus described the invention, what is claimed is—

1. The combination with a chair having arms, of a hinge member having an attaching, leaf secured to one of said arms, inbent flanges being formed on the side edges of the other leaf to form guides, a table mounted to slide in said guides, a pin secured to the inner surface of said table adjacent one end thereof, said pin adapted to engage the flanged leaf to limit the inward movement of the table, and a second pin secured to the inner surface of the table adjacent its opposite end, said pin adapted to engage a notch provided in the other arm of the chair, to lock the table in operative position, and adapted to engage said attaching leaf to limit movement of the table in the opposite direction.

2. The combination with a chair having arms, of a hinge member including an attaching leaf secured to one of said arms and a guide leaf having inbent flanges formed thereon, a table mounted between said guides

for slidable movement, means for securing the inner end of the table to the opposite arm of the chair when the table is in its operative horizontal position, said means adapted to engage the attaching leaf of the hinge to limit the movement of the table into inoperative position, and means provided upon the outer end of the table for engagement with the guide leaf to limit the

movement of the table into operative position. 10

In testimony whereof I affix my signature in presence of two witnesses.

EDWIN B. SCHMUCKER.
